UNITED STATES PATENT OFFICE

2,637,502

POCKETED HAMMER ROTOR FOR
PULVERIZING MACHINESFred C. Bond, West Allis, Wis., assignor to Allis-
Chalmers Manufacturing Company, Milwaukee,
Wis., a corporation of Delaware

Application June 7, 1949, Serial No. 97,618

1 Claim. (Cl. 241—194)

1 The present invention relates to pulverizing machines and more particularly to such machines as utilize rotating hammers, and the principal object of the invention is to provide new and improved pulverizing machines and hammers therefor.

Another object of this invention is to provide a pulverizing machine in which a maximum amount of the material is crushed on itself by impact, with only a relatively small amount of metal surfaces exposed.

Another object is to provide a pulverizing machine which utilizes the principle of centrifugal force in forming a hard, dense layer of the material being reduced such that the exposed surface of the layer forms an advancing impact surface.

Other objects will appear hereinafter as the description of the invention proceeds.

The novel features of the invention and how the objects are attained will appear more fully from this specification and the accompanying drawing showing one embodiment of the invention and forming a part of this application, and all of these novel features are intended to be pointed out in the claim.

In the drawing:

Fig. 1 is a vertical sectional elevation taken through a pulverizing machine having the invention applied thereto, taken on line I—I of Fig. 2;

Fig. 2 is a vertical sectional elevation of the machine shown in Fig. 1, taken on the line II—II;

Fig. 3 is an enlarged top view of one of the hammers shown in Fig. 1; and

Fig. 4 is a sectional view of the hammer shown in Fig. 3, taken along line IV—IV.

The pulverizer consists of a stepped shaft 10 mounted in bearings 11 which are supported by the stationary pulverizer casing or frame 12. A driving pulley 13 is fixed to one of the overhanging ends of the shaft 10, while a flywheel 14 is mounted on the opposite overhanging end thereof.

Suspension members 15 are provided for pivotally carrying the hammers as will appear. The members 15 have two parallel annular flanges extending outwardly from respective central hubs which are keyed to the shaft 10. The new and improved hammers 19 have parallel shanks 20 suspended from pins 21 which pass through the parallel flanges of the members 15. The hammers 19 are free to oscillate about the pins 21, the pins 21 being fixed or locked to the respective hammer carrying members 15. It is to be understood that the means shown for adapting the

hammers 19 to be rotated by the rotor shaft 10 is preferred but that any suitable fastening means may be used.

5 A hopper 22 is mounted on top of the casing 12 for feeding the material to be reduced into the reduction chamber 23 and a series of individual grate bars 24 are secured in the lower part of the casing 12, the use of such bars being optional depending on the degree of reduction desired.

10 The side wall of the casing 12 is lined with V-shaped channel members 25 shaped and arranged to form pockets which fill with the material being reduced during operation such that the material being thrown by the hammers 19 is broken by impact against like material in the members 25. However, the lining of the side wall of the casing 12 may be of any suitable construction in that the type of lining in itself bears no relation to the invention.

15 20 Although Fig. 1 shows four hammer members 19 secured to the suspension members 15 it is to be understood that any suitable number of hammers may be used. However, if only one hammer is used the shaft 10 will be unbalanced and for satisfactory operation this unbalance would have to be compensated for by attaching suitable weights on the opposite side of the suspension members 15.

25 In general, each hammer 19 is formed with a pocket 30 so constructed that when the shaft 10 is rotated at a suitable speed a layer of the material being reduced accumulates therein and the exposed surface of the layer forms an advancing impact surface 31 (see Fig. 1). The particular shape of the hammer 19 shown is a preferred embodiment but it is to be understood that certain deviations may be made from such shape without departing from the spirit and scope of the invention.

30 35 40 As shown in Fig. 1, the inside surface 32 of the radially outermost retaining wall 33 of the pocket 30 is normal to radial planes, radiating from and including the axis of the shaft 10 and passing through the wall 33, and the bottom surface 34 of the pocket 30 lies generally in a radial plane. The inside surfaces of the pocket 30 may be corrugated as shown in the drawing.

45 50 55 The theory or principle of the invention lies in constructing a pocket 30 in the hammer 19 in such a manner that the material accumulated therein, during operation, will not be displaced from the pocket 30 by the action of centrifugal force on such material. The material thus confined is subjected to the joint effects of centrifugal forces acting in a radially outward direction

and the impaction of the material being reduced on the exposed surface 31 of the confined material such that the confined material in the pocket 30 is bonded into a hard, dense, tightly packed mass.

To utilize the above principle to the best advantage the material, accumulated in each hammer pocket 30, must be effectively prevented from becoming displaced therefrom. The construction of the inside surface 32 of the retaining wall 33 normal to radial planes passing through the wall 33 thereby makes such surface 32 also normal to the direction in which the centrifugal forces urge the material accumulated such that the portions of the material adjacent the wall 32 tends to pack against it. As the magnitude of centrifugal force acting on a body revolving at a constant angular velocity increases with the distance such body is away from the axis of revolution, in this case the axis of shaft 10, it is to be noted that the portion 36 of the material immediately adjacent the surface 32 is exerting a greater force per unit area on the surface 32 than the force per unit area exerted on that portion 36 by material 37 adjacent thereto on the radially inward side. For that reason the high friction between the inside retaining surface 32 and the material adjacent that surface will not be overcome.

The bottom surface 34 of the pocket and the perimeter 35 of the pocket opening are preferably in radial planes such that the tangential cross sectional area of the pocket diminishes in a radially inward direction. Therefore, not only is the force per unit area decreasing in the direction of the axis, as shown above, but also the tangential cross sectional area. As the friction between the particles of the material decreases from the retaining surface 32 in a radially inward direction, the radially inner portions of the material will tend to pack tightly against the radially outer portions but not force them out of the pocket. This tendency of the particles to pack together in an outwardly radial direction coupled with the impaction of the material being reduced on the exposed surface 31 of the accumulated material in the pocket 30 causes this accumulated material to be bonded into a hard, dense layer. When the exposed surface 31 of this layer becomes worn in operation the portions so worn are continuously replaced by portions of the material being reduced. Therefore it will be apparent that there will

always be a layer of material retained in the pocket 30.

From the foregoing it will be apparent to those skilled in the art that the illustrated embodiment of the invention provides new and improved pulverizing machines and hammers therefor, and accordingly accomplishes the objects of the invention. On the other hand, it will also be obvious to those skilled in the art that the illustrated embodiment of the invention may be variously changed and modified or features thereof singly or collectively, embodied in other combinations than those illustrated without departing from the spirit of the invention and accordingly the disclosure herein is illustrative only, and the invention is not limited thereto.

It is claimed and desired to secure by Letters Patent:

A pulverizing machine, comprising, a casing, a hammer carrying member rotatably mounted in said casing, a hammer pivotally mounted on said member about an axis parallel to the axis of rotation of said member, said hammer having surfaces forming a pocket therein with an opening in a generally radial plane with respect to said axis of rotation for accumulating a layer of the material being reduced when said member is rotated about said axis such that the exposed surface of said layer forms an advancing impact surface, and at least some of said surfaces of said pocket being corrugated to resist displacement by centrifugal force of portions of said layer adjacent the corrugated portions of said surfaces.

FRED C. BOND.
